HERMANN HILL, OF DETROIT, MICHIGAN, ASSIGNOR TO SYRACUSE WASHING MACHINE CORPORATION, OF SYRACUSE, NEW YORK, A CORPORATION OF DELAWARE

SHOE MOUNTING FOR IRONING MACHINES

Application filed August 29, 1928. Serial No. 302,767.

This invention relates to a power-driven ironing machine and as illustrated in the drawings, the ironer is adapted for the use of electricity.

5 In an electrically operated ironing machine, the ironer or as I prefer to term it, the shoe, which cooperates with the roll, is mounted on a rocker arm which is adapted to be moved by an operating shaft driven 10 by some part of the mechanism of the machine, which mechanism is in turn operated by an electric motor.

It is the principal object of my invention to provide new and improved means for 15 mounting the shoe on the rocker arm whereby other ancillary objects are attained, which will be brought out in the descriptive matter to follow.

Since the mechanism for operating the 20 roll and the shaft which manipulates the shoe may be varied over wide limits, I have therefore only shown the mechanism relating to the shoe mounting per se. In the drawings,

25 Figure 1 is a sectional view through the ironing shoe and mounting means for carrying and operating the shoe. This section is taken on the line 1—1 of Figure 2.

Figure 2 is a view looking at the shoe 30 and mounting means from the right of Figure 1, the shoe and operating shaft being cut off at one end.

Figure 3 is a plan view of the attachment plate and bracket which are attached 35 directly to the shoe.

Figure 4 is a part sectional and elevational view on the line 4—4 of Figure 3.

Referring now to the details wherein like 40 numbers refer to corresponding parts in the drawings, 1 illustrates the roll of the ironing machine. 2 is an operating shaft driven by some part of the ironing machine mechanism that is operated by an electric motor. Securely attached to the 45 shaft 2 as by a key 3 and set screw 4, is a rocker arm composed of two pieces 5 and 6, the piece 6 being pivoted on the piece 5 by means of a pivot pin 7 which is supported by the arms 8 and 9 which extend upwardly from the piece 5. As will be seen from

Figures 1 and 2, the piece 6 is channel-shaped having the web of the channel terminating in a lug 10 which carries adjusting screw 11 for the purpose of adjusting the position of the piece 6 about the pivot 55 pin 7.

The upper end of the flanges of the piece 6, is provided with holes and through these holes, passes a pivot pin 12. The pivot pin 12 carries a bracket 13, the end of which is 60 positioned between the two flanges of the piece 6.

The piece 5 of the rocker arm is provided with a pocket or recess 14, within which is positioned a cantilever spring 65 which as illustrated, is made up of four leaves, 15, 16, 17, and 18, the longest leaf, 18 resting against the end of the bracket 13. The leaves of this cantilever spring are securely held in the pocket or recess 14 in any 70 satisfactory manner as by a set screw 19.

By adjusting the screw 11, the desired amount of tension can be stored in the cantilever spring, and it will be clear that this tension will be permanent and substantially 75 independent of the mechanism which operates the shaft 2.

The bracket 13 is attached to a multiple flat-leaf spring 20 by means of a heavy cap screw 21. The spring 20 is positioned in a 80 pocket 22 of a plate 23, being held in the pocket 22 by means of clamps 24 and 25 which are held to plate 23 by screws 26 and 27. The plate 23 is preferably made of a casting and in order to save doing machine 85 work on the pocket 22, I prefer to use spacers 28 and 29 between the clamps 24 and 25 and the plate 23, which spacers take up variations in the casting and also allow the clamps 24 and 25 to be drawn down 90 securely without actually clamping against the ends of the spring 20 which is left to move freely in the pocket, there being side clearances 30 and 31, as shown in Figure 3. This method of mounting the bracket 95 13, allows the plate 23 and the entire shoe 32 fastened to the plate, to have a certain endwise, up-and-down, as well as a slightly rotary motion, in order that the shoe 32 may adjust itself to the contour of the roll 100

1. The plate 23 is fastened to a metallic member 33 by means of the holes 34 and bolts 35, it being understood that the metallic member 33 is provided with a flat surface as indicated by the dotted line 36 (Fig. 2) to receive the flat surface of the plate 23.

The shoe 32 carries the heating elements 37 and 38 which are of a special design, but since they form no part of the present invention, will not be further described herein.

10 However, to direct the heat toward that part of the shoe in contact with the roll 1, a strip of asbestos 39 is used between the metallic member 33 and the heating units 37 and 38.

15 A cover 48 is fastened by bolts 49 to the shoe 32, a strip of asbestos 50 being used to prevent the heat from radiating from the back side of the shoe. It is to be understood that the metallic member 33 is fastened in any satisfactory manner to the shoe 32, as by bolts 51 (only one being shown).

An important feature of my invention is the method of transmitting the applying force to the shoe 32. This is accomplished in 25 the following manner:

The backside of the plate 23 is provided with a slight recess 40, and in this recess, is positioned a strip 41, preferably of cold rolled steel which has formed in it a shallow cup 30 42 to fit over the rounded head of the cap screw 21. In the metallic member 33 there is formed a cup 43 corresponding in contour to the cup 42, one cup being nested into the other with preferably a piece of asbestos 44 35 interposed to prevent as much as possible the heat from coming out of the rear part of the shoe.

This construction and association of the parts 21, 41, 42, and 43, together with the 40 spring 20, provides a swiveling or equalizing connection between the shoe 32 and the rocker arm that allows the shoe to take up a perfect alignment on the roll 1. However, to get the first adjustment between the shoe 32 and the 45 roll 1 generally correct, a set screw 45 is carried by the piece 6 and is adapted to engage a projection 46 on the bracket 13, but after this adjustment has once been made, the flexible union of the shoe and the bracket 13 as just described, will take care of all of the other variations, including thickness and irregularity 50 of the work passed between the roll 1 and the shoe 32.

By providing the adjustment between the 55 pieces 5 and 6 by means of the screw 11 as previously described, a very desirable and important object is attained, for by this arrangement, at the time when the shoe reaches the roll due to the turning of the operating shaft 60 2, the cantilever spring is under full tension which is only slightly increased when the operating mechanism of the machine, which may be an eccentric device, has reached the 65 limit of its movement for applying the shoe 70 to the roll. When the shoe is in full contact

with the roll, the set screw 11 will be free from contact with the piece 5, as indicated by the space 47, and pressure is transmitted from the rocker arm to the bracket 13 and the head of the cap screw 21 to the swivel joint 75 as described.

Since this rocker arm is fully exposed on the machine, this adjustment may be quickly and easily made and the clearance observed as above indicated, proves that the iron is in 75 full pressure contact with the roll.

While I have shown the cantilever spring as being made up of four leaves of different lengths, it is obvious that the number and length of these springs may be varied to suit 80 the condition. It is also obvious that the spring 20 may be made up of a more or less number of these springs than the four shown in the drawings, and likewise, other details may be varied without departing from the 85 spirit of my invention as limited by the scope of the appended claims.

Having thus described my invention, what I claim is:

1. Means for mounting an ironing shoe 90 on an ironing machine including, a rocker arm with means for actuating the same, a bracket pivotally carried on the free end of the rocker arm, a member having some resilience held to one end of the bracket at 95 right angles thereto, a plate having means for attachment to a part of the shoe, means for loosely anchoring said member to said plate, a metallic member carried by the shoe and having a depression therein, and a metallic member having a cup therein to nest within said depression, said last mentioned metallic member loosely fitting within a guide recess in said plate.

2. Means for mounting an ironing shoe on 105 an ironing machine including, a rocker arm with means for actuating the same, a bracket pivotally carried on the free end of the rocker arm, a flat member fastened at right angles to the end of said bracket by a cap screw, a plate having a recess on one side within which said flat member is loosely positioned, means for holding said flat member in its recess in a loose manner, means for anchoring said plate to a shoe member, said shoe member having a cup therein and a metal piece having a cup to fit in the first cup, said metal piece being positioned by said plate and held in operative position against said shoe member by the head of said cap screw 110 being positioned within the cup of said metal piece for the purpose described.

3. In an ironing machine having an ironing roll and shoe, a rocker arm provided with means for actuating it, means for carrying 115 the ironing shoe on the rocker arm so the shoe may swivel and otherwise move so as to be parallel with the roll of the machine, said carrying means including, a bracket 120 movably carried on the free end of the rocker 125

arm, a plate fastened to a shoe member, said shoe member having a cup therein, a member between the plate and shoe member and having a cup to nest in the first mentioned cup and a member connecting in loose relationship the plate to the bracket.

4. In an ironing machine having an ironing roll and shoe, a rocker arm provided with means for actuating it, means for carrying the ironing shoe on the rocker arm so the shoe may swivel and otherwise move so as to be parallel with the roll of the machine, said carrying means including, a bracket movably carried on the free end of the rocker arm, a plate fastened to a shoe member, said shoe member having a cup therein, a member freely associated with the plate and having a cup held in nesting position with the first-mentioned cup by said plate and a member rigidly fastened to the bracket at its central portion and loosely held to the plate at its end.

5. In an ironing machine having an ironing roll and shoe, a rocker arm provided with means for actuating it, means for carrying the ironing shoe on the rocker arm so the shoe may swivel and otherwise move so as to be parallel with the roll of the machine, said carrying means including, a bracket movably carried on the free end of the rocker arm, a plate fastened to a shoe member, said shoe member having a cup therein, a connecting member positioned in a recess on one side of said plate, said connecting member having a cup fitting within the first-mentioned cup and a member held at its center to the bracket by a cap screw and loosely supported at its ends on said plate so the head of said cap screw fits within the cup of said connecting member as and for the purposes described.

6. Means for mounting an ironing shoe on an ironing machine comprising a rocker arm with means for actuating the same, a bracket pivotally carried on the free end of the rocker arm, a member having some resiliency held to one end of the bracket, a plate having means for attachment to a part of the shoe, means for loosely anchoring said member to said plate, a member carried by the shoe and having a depression therein, and another member having a raised portion thereon adapted to register with said depression, said last mentioned member loosely fitting on said plate.

In testimony whereof, I affix my signature.
HERMANN HILL.
